[57] ABSTRACT

A staggered needle cut-pile tufting machine in which the loopers cooperating with one row of needles are longer than the loopers cooperating with the other row of needles so that each looper may seize a loop from its associated needle. The loopers are constructed and positioned in the looper bar with the throats of all the loopers aligned. The loop cutting knives are mounted in a single oscillating knife block and are aligned to cut substantially at the throat of a respective cooperating looper. The effect is that neither loop seizure nor loop cutting are compromised. Also disclosed is a needle bar capable of shifting laterally with respect to the loopers.

STAGGERED NEEDLE CUT-PILE TUFTING MACHINE

BACKGROUND OF THE INVENTION

The present invention relates to tufting machines, and more particularly to an improved apparatus and method for manufacturing cut-pile fabric on a tufting machine having laterally spaced parallel rows of needles.

It is known to create a dense loop pile fabric by a tufting machine having parallel rows of needles laterally spaced to provide a smaller gauge (U.S. Pat. of Webb No. 3,492,956). However, cut-pile tufted fabric, which is today of greater popularity, has not been produced with comparable density as to the loop pile fabric. One reason for this is the space problem created by the many gauge parts. In cut-pile tufting machines each needle includes an associated looper for seizing a loop and an associated knife for cutting the seized loops. When parallel rows of staggered needles are applied in a tufting machine the loopers have been either spaced in separate looper bars, spaced differently in one supporting looper bar as illustrated in the aforesaid Webb Patent, or are of different sizes as illustrated in U.S. Patent of Woodcock, No. 3,440,983. In a cut-pile tufting machine the loops are fed onto the looper bills and the knives cut when the loop is at the throat at the rear of the bill after there are a number of seized loops positioned on the bill. Experience has taught that this cutting relationship should be maintained between all the loopers and knives. When manufacturing cut-pile fabrics, it would be necessary to have knives of different lengths or knives mounted on different oscillating knife blocks if the loopers are mounted in space separate looper bars or are spaced differently in a single row looper bar. This for obvious reasons is not desirable. In the aforesaid Woodcock Patent in order to have the knives cut at the looper throats of the different size loopers, the knives were mounted in blocks having alternately angled grooves. From a manufacturing standpoint this approach is of course not desirable.

SUMMARY OF THE INVENTION

To overcome the limitations of the prior art the present invention provides apparatus for producing a dense cut-pile fabric on a tufting machine having first and second laterally spaced parallel rows of needles. The loopers associated with the first row have a loop-seizing bill portion longer than that of the loopers associated with the second row by substantially the spacing between the first and second rows, and all the loopers are positioned in a supporting looper bar with the throats of the loopers substantially aligned laterally. The knives associated with the loopers are positioned in a supporting knife bar with all the knives laterally aligned so as to cut the loops at the throat of the associated looper.

Another feature of the invention provides the loop seizing portion of the bill of the longer bill loopers with a slight angular undercut relative to the shorter bill loopers.

Another feature of the invention is the inclusion of a means for imparting relative lateral movement between the needles and the backing fabric in accordance with a pattern to provide unique cut-pile pattern effects wherein none of the yarn is hidden, and therefore wasted, as it is when using loop or loop/cut machines with a yarn feed pattern attachment.

It is therefore the primary object of this invention to provide a cut-pile tufting machine having first and second laterally spaced parallel rows of needles which can provide unique tufted fabric.

BRIEF DESCRIPTION OF THE DRAWINGS

The particular features and advantages of the invention as well as other objects will become apparent from the following description taken in connection with the accompanying drawings, in which:

FIG. 1 is a fragmentary sectional view of a tufting machine embodying the present invention;

FIG. 2 is a partial perspective view of the loop forming and cutting mechanism of the present invention;

FIG. 3 is a side view of the mechanism illustrated in FIG. 2;

FIG. 4 is a cross sectional view taken substantially along line 4-4 of FIG. 3;

FIG. 5 is a side elevational view of the loop forming and severing mechanism of FIG. 1 at an instant during the operating cycle; and

FIG. 6 is a diagrammatic view of a typical patterned cut-pile fabric produced by the tufting machine illustrated in FIG. 1.

DESCRIPTION OF THE PREFERRED EMBODIMENT

Referring now to the accompanying drawings, there is illustrated a portion of a tufting machine comprising a frame 10 including a head 12 over-hanging a bed 14. A backing fabric F in the form of a web is passed from front to rear across a bed plate 16 in the direction of the arrow A in FIG. 1 by a conventional feed mechanism including feed rolls 18 and 20. Mounted in the head 12 for endwise reciprocation is a push rod 22 which at its lower end carries a needle bar 24 that in turn carries two parallel rows of needles 26 and 28. The needles in the rear row 28 are spaced from the needle in the front row 26 and are staggered relatively to the front row as best illustrated in FIG. 2. The stagger is such that needles in the rear row are off-set substantially mid-way between the needles in the front row. Thus, the gauge of the machine is substantially half the distance between adjacent needles in each row. Both rows of needles in the preferred embodiment are mounted in a common needle bar 24 which is slidable in a channel formed in a needle bar carrier 30 so that the needle bar 24 can be shifted laterally in a manner disclosed in U.S. Pat. of Bryant, No. 3,026,830. As illustrated in this patent the timing and amount of the shifting is controlled by a pattern mechanism such as a cam. It should be understood that the needles 26 and 28 may be mounted in separate needle bars which may be slidably positioned individually or separately as known in the art. The rod 22 is adapted to be reciprocated by conventional mechanism (not shown) including a crank rod that cooperates with an eccentric upon a main shaft journaled longitudinally of the head. In operation, the needles are, of course, threaded with yarn Y feed by conventional means.

Longitudinally of the bed 14 there is journaled a hook or looper shaft 32 on which is mounted a bracket 34 carrying a looper bar 36 having a plurality of parallel spaced slots 38 adapted to receive loopers 40 and 42. In order to form the loops or tufts during successive penetrations of the needles, there is provided a looper for each needle for holding the loop or tuft during the

upward stroke of the needles. Thus, each needle 26 has an associated looper 40 and each needle 28 has an associated looper 42 for seizing a loop deposited by the associated needle. The looper shaft 32 is oscillated in a conventional manner through means driven off the main shaft. Each looper 40 and 42 includes a body portion 44 including a blade 46, and a shank 48 adapted to be received within the slots 38. Each looper 42 further includes a loop penetrating bill 50 angularly extending from the body portion, and each looper 40 includes a bill 52 angularly extending from its body portion. Between the blade 46 of each body portion and the respective bill 50 and 52 is what shall be defined as the looper throat 54. In accordance with the present invention, the throats, 54 of all the loopers 40 and 42 are substantially aligned laterally as best illustrated in the elevational view of FIG. 3. Thus, the bill portions 52 of the loopers 40 are longer than the bills of the loopers 42 to compensate for the spacing between the needles 26 and 28 in the direction of feed.

In order to form cut-pile each looper has an associated knife 56 carried by a knife bar 58 mounted on a shaft 60 which is conventionally oscillated through mechanism driven off the main shaft in timed relation to the oscillation of the loopers. Each knife 56 includes a cutting edge 62 which, as best illustrated in FIG. 4, is biased by the flexibility of the knives against the side of the looper and is adapted to cooperate with the bottom edge of each looper bill which acts as a ledger to sever the loops on the blade to form cut-pile. In accordance with the present invention each knife associated with the looper 42 is aligned with each knife associated with the loopers 40. For optimum cutting the knives operate at the rear portion of the bills, and preferably at the throat, so that several loops may be present on the bill. The loops are severed by the knives as they move back on the bill as the fabric F is fed and thus carries the loops into the area where the knife is operative. Since in accordance with the present invention the throats of all the loopers are aligned, and the knives are aligned, each knife will cut at the throat of its associated looper.

In the operation of the above mechanism the needles 26 and 28 are reciprocated to penetrate the fabric F and to project the loops of yarn there through. As the needle rises to cast a loop, the loopers are advanced in its loop penetrating stroke wherein the bills 50 and 52 enter respective loops of yarn presented by the needle. The loops remain on the hook and as the fabric is advanced, they are carried back on the bill and are eventually severed by the knives 56 at the throats 54. FIG. 5 best illustrates this operation wherein there is shown loops 64 formed by the interaction of the needles 26 with the loopers 40 and loops 65 formed by the interaction of the needles 28 and the loopers 42. Each of these loops are carried back on the respective bills 50 and 52 and are severed at the throat 54 by the knives 56 to produce cut-pile 66.

It has been found that because of the properties of certain yarns, notably the polyesters, the loops 64 formed on the loopers 40 tend to pile up and slip off the longer bills 52 when the underside of the bills 52 are substantially parallel to the needle plate 16 during loop penetration. It has been found that if the underside of the bills 52 are under-cut by an angle ϕ of approximately 5 to 7 degrees this problem is alleviated. Thus, when properly positioned in the looper bar 36 the bot-

tom edge of the bills 52 of the longer bill loopers 40 may be at an angle of approximately 5 to 7 degrees to the equivalent loop seizing portion of the shorter bill loopers.

During the operation of a machine incorporating the present invention, it has been found that unique and desirable cut-pile patterns are obtained when relative lateral shifting movement between the needles and the backing fabric are provided. Such relative movement may be provided by a sliding needle bar arrangement as illustrated in the aforesaid Bryant U.S. Pat. No. 3,026,830 or it may be provided by a shifting needle plate as disclosed in U.S. Pat. of Card, No. 3,301,205. This patterning effect is especially interesting when different color yarn is selectively threaded into the needles of the parallel rows. For example, FIG. 6 illustrates a typical patterned cut-pile fabric manufactured by the machine illustrated in FIG. 1 and in which a yarn of a first color 68 is threaded in a three to one relationship to a yarn of a second color 70, and relative lateral movement between the needles and the backing fabric is imparted by an amount corresponding to the spacing between the needles in one row every other penetration of the needles. It should be understood that the lateral shifting movement must occur with the present invention by an amount comprising multiples of the spacing between needles in each row, because the loopers 40 must correspond with the needles 26 and the loopers 42 must correspond with the needles 28. Patterning of cut-pile fabric accomplished in this manner rather than by the use of a yarn feed roll attachment, as is generally used with loop pile and loop/cut-pile leaves every yarn visible. This is not the case with loop pile or loop/cut-pile in which some yarn is inserted which is hidden as short loops in the pattern. Thus no yarn is lost in the pattern as it is with loop and loop/cut-pile.

Numerous alterations of the structure herein disclosed will suggest themselves to those skilled in the art. However, it is to be understood that the present disclosure relates to a preferred embodiment of the invention which is for purposes of illustration only and not to be construed as a limitation of the invention. All such modifications which do not depart from the spirit of the invention are intended to be included within the scope of the appended claims.

Having thus described the nature of the invention, what is claimed herein is:

1. In a tufting machine for making cut-pile fabric, means for supporting a backing fabric fed from front to rear of the machine, a needle bar means carrying front and rear laterally extending spaced rows of yarn carrying needles disposed on one side of the backing fabric, the needles in the rear row being staggered relatively to the front row, means for reciprocating the needles to penetrate and insert loops of yarn through the backing fabric, a looper associated with each needle disposed on the opposite side of the backing fabric from said needles, each looper including a body portion and a loop penetrating bill angularly extending from said body portion and defining a throat therebetween, the bills of the loopers associated with the front row of needles being longer than the bills of the other loopers by substantially the spacing between the front and rear row, means for supporting the body portion of said loopers with all the throats substantially aligned laterally, means for actuating said loopers so that said bills enter respective loops of yarn presented by said needles

to seize and hold the loops when the needles are withdrawn, a knife disposed on one side of each hook and having a cutting edge for cooperating with the respective blade adjacent the throat for severing loops thereon to form cut-pile, means for supporting said knives substantially aligned laterally, and means for actuating said knives in timed relation to the actuation of said loopers for movement in a path wherein said cutting edges are moved into cutting engagement with the respective blade.

2. In a tufting machine as recited in claim 1 wherein the loop seizing portion of the bills of the longer bill loopers are at an angle to the loop seizing portion of the shorter bill loopers.

3. In a tufting machine as recited in claim 2 wherein said angle is approximately 5° to 7°

4. In a tufting machine as recited in claim 1 including means for imparting relative lateral movement between

said needles and said backing fabric in accordance with a pattern.

5. A looper assembly for a tufting machine comprising a looper bar, a plurality of loopers, each looper including a body portion and a loop penetrating and seizing bill angularly extending from said body portion and defining a throat there between, means for mounting said body portions in said looper bar in a row with all the throats substantially aligned, and the bills on alternate loopers being longer than the bills of the adjacent loopers.

6. A looper assembly as recited in claim 5 wherein the loop seizing portion of the bill of the longer bill loopers are at an angle to the loop seizing portion of the shorter bill loopers.

7. A looper assembly as recited in claim 6 wherein said angle is approximately 5° to 7°
